United States Patent Office

Des. 188,049
Patented May 31, 1960

188,049

SOFA

Ralph M. Galloway, 601 S. Audubon Ave., Tampa, Fla.

Filed Oct. 24, 1958, Ser. No. 53,148

Term of patent 14 years

(Cl. D15—11)

I claim:

The ornamental design for a sofa, as shown.
